ELECTRICAL VAPORIZER FOR INTERNAL-COMBUSTION ENGINES.

No. 909,899.

Specification of Letters Patent.

Patented Jan. 19, 1909.

Original application filed February 11, 1907, Serial No. 356,792. This application filed April 16, 1907.
Serial No. 868,554.

To all whom it may concern:

Be it known that we, HARRY HERTZBERG and ABBOT A. Low, citizens of the United States, residing at the city of New York, borough of Brooklyn, State of New York, and Horseshoe, State of New York, respectively, have invented a certain new and useful Electrical Vaporizer for Internal-Combustion Engines, of which the following is a specification.

This invention is a vaporizer particularly adapted for use in internal combustion engines.

The subject matter of this application is a division of a prior application filed by us on February 11, 1907, Serial No. 356,792.

The object of our invention is to quickly heat a surface against which petroleum or other liquid combustible is sprayed in starting the engine, whereby a sufficient temperature is produced in the vaporizer within a very short time for the purpose of converting the liquid fuel into a vapor, the latter being mixed with air so as to produce an explosive charge.

Our invention is an electrically heated vaporizer located internally of the combustion chamber (or piston cylinder) of the engine.

The vaporizer of our invention is simple in construction, economical to manufacture and install, efficient in operation, and also particularly compact, for the reason that it occupies very little space in the combustion cylinder of the engine.

In the accompanying drawings, we have illustrated one practical embodiment of the invention, but the construction shown therein is to be understood as illustrative only, and not as defining the limits of the invention.

Figure 1 is a vertical section, partly in elevation, illustrating one embodiment of the invention in connection with the piston cylinder, and one style of mixing chamber and intake valve. Fig. 2 is a vertical section of another form of our vaporizer which is constructed for the circulation of a cooling medium therethrough when the engine is in operation, said vaporizer being shown removed from the engine cylinder. Fig. 3 is a detail view, partly in elevation and partly in section, illustrating another form of the electrically heated vaporizer adapted for use

internally of the engine cylinder. Fig. 4 is a horizontal section on the line 4—4 of Fig. 55 3 showing the outer tube of said vaporizer partly broken away for the purpose of illustrating the electrical resistance therein. Fig. 5 is a detail view of a rheostat of the electrical resistance contemplated by this invention.

In Fig. 1 of the drawings we have shown one type of internal combustion engine wherein we may employ our new form of vaporizer which is adapted to be heated initially by an electric current for the purpose of converting a combustible liquid into a vapor when starting the engine into operation, after which the parts of the engine become heated to such an extent as to vaporize the subsequent charges of the combustible liquid, thereby insuring the continued operation of the engine. In said Fig. 1 the combustion chamber or piston cylinder is indicated at A, and a part of the piston is indicated at a. One end of the cylinder is closed by a head, B, in which is provided an intake passage, b, the latter being closed by an intake valve, C. Any suitable means may be employed for mechanically operating said intake valve from a moving part of the engine, or the said intake valve may be operated by the suction created in the engine cylinder by the reciprocation of the piston therein. As shown, however, the valve, C, is provided with a stem, c, on which acts a spring, C', for holding the valve, C, normally on its seat in the cylinder head.

D is a casing secured to the cylinder, A, or the head, B, in any usual or preferred way. 90 Said casing forms a mixing chamber, d, and a circulating chamber, d', the latter being next to the head, B, and permitting the circulation of a cooling medium, such as water. The casing is shown as having an air inlet, e, 95 the area of which is controlled by any suitable form of valve or regulator, E, adapted to regulate the volume of atmospheric air which is to be supplied to the mixing chamber, d.

Any suitable means may be employed for supplying a combustible liquid to the chamber, d. Such liquid may be of any suitable or preferred character, but in the engine shown by the drawings we contemplate supplying kerosene to the mixing chamber.

A jet nozzle, F, is attached to the hood, D, and as shown, said nozzle is arranged to throw a jet of combustible liquid across the chamber, d, and against or through the diaphragm, G. Said diaphragm may be of any suitable nature, but as shown it consists of a piece of metallic gauze arranged vertically within the mixing chamber and in the path of the jet of liquid from the nozzle, F, whereby the diaphragm is adapted to break up the jet of liquid and convert the same into a spray, such liquid spray being brought into contact with the diaphragm when the engine is started. It is to be understood that a jet of combustible liquid is forced under pressure, and at intervals, into the mixing chamber by a suitable mechanical appliance, such as a pump, the latter being operated by the engine.

According to the present invention we employ an electrically heated vaporizer which is located within a combustion chamber or piston cylinder of the engine, said vaporizer being heated electrically when the engine is started for the purpose of presenting a hot surface to the combustible liquid in order to vaporize the latter and furnish the combustible charge which is adapted to be exploded by an igniter, the latter being located also within the aforesaid chamber or cylinder. The vaporizer of this invention is heated electrically for a short period of time when starting the engine, and it is employed merely for the purpose of vaporizing the first number of charges admitted to the engine when starting the same, after which the current of electric energy is cut off from said vaporizer for the reason that the parts of the engine become heated to such a temperature as will convert the liquid into vapor, whereby the engine, after starting the same, will operate automatically and independently of the vaporizer of this invention.

Various constructions of the internally located vaporizer are shown in Figs. 1 to 4 inclusive, but we will describe the construction represented in Fig. 1, and thereafter set forth in detail the constructions of the other vaporizers shown in Fig. 2 and in Figs. 3 and 4.

The vaporizer, H, of Fig. 1 is arranged in the path of a mixture of air and combustible liquid, in order that said liquid may be brought in contact with the heated surface of the vaporizer when the intake valve is opened in the operation of the engine. As shown, said vaporizer is composed of metallic plates or masses, h, h', arranged to clamp between themselves an electrical resistance, h², the latter being insulated from metallic contact with said plates or masses by layers of insulating material, h³, preferably composed of thin layers of mica. It is preferred to employ a thin metallic wire or

ribbon as the electrical resistance, and to 65 coil said wire or ribbon on a core of insulating material, composed of a layer of mica, h⁴. The core and the resistance wire thereon is arranged between the insulating mica layers, h³, and said resistance wire or ribbon 70 is in mechanical contact, practically, with the metallic masses, h, h', whereby the heat developed in the resistance when the electric current is admitted thereto is absorbed by the metallic masses practically as fast as the 75 heat is generated. This construction is advantageous for the reason that the masses of metal will become heated very quickly by an electric current in order to furnish a hot vaporizing surface to the combustible liquid 80 as it is admitted with the air to the engine cylinder.

Any suitable means may be employed for supporting the vaporizer within the combustion chamber or piston cylinder of the 85 engine, but as shown in Fig. 1, it is adapted to be suspended below the intake valve, C, by hangers, i. The electrical current for heating the vaporizer is supplied to, and conveyed from, the electrical resistance, h², by 90 conductors, j, the latter being led through suitable bushings, k, k', which are shown as being fastened to the head, B, and a flanged part, d², of the casing, D. The operation of the engine shown in Fig. 1 will be readily 95 understood from the foregoing description, when the valve, C, is opened, a mixture of air and liquid combustible, such as kerosene, is admitted by the intake passage, b, into the combustion chamber. Owing to the arrangement of the vaporizer, H, in the path of the inflowing mixture, the liquid combustible is brought into contact with the hot surfaces of said vaporizer, whereby said liquid combustible is converted into a vapor, 100 and the air is heated, thus producing an explosive charge which is adapted to be ignited by the operation of a spark plug, I, or any equivalent form of igniter. It will 105 be understood that before starting the engine is in a cold condition, and should an explosive charge be admitted to the engine while in such condition, the liquid combustible or kerosene of such explosive charge would condense when brought into contact 110 with such cold surfaces. To overcome this objection and enable the engine to be started promptly, we provide the electrically heated vaporizer. Before starting the engine an electrical current is admitted to the resistance of said vaporizer for the purpose of initially and quickly heating the latter. Now when the engine is cranked and the valve, C, is opened, the mixture of air and liquid combustible is admitted to the cylinder, at which time the liquid combustible is 115 converted into vapor and the explosive charge is produced and adapted to be sub- 120 125

sequently ignited by the operation of the igniter, I.

In Fig. 2 of the drawings we have shown another embodiment of our invention consisting of a vaporizer adapted to be electrically heated when starting the engine, said vaporizer of Fig. 2 being constructed for the circulation therethrough of a cooling medium when the engine is heated up and in operation, whereby the vaporizer is prevented from becoming too highly heated in the operation of the engine. Said vaporizer is represented as a ring or annulus adapted to be attached to, or suspended from, the cylinder head, B, in any suitable or preferred way, the annular vaporizer being in the path of the liquid combustible or the explosive charge admitted by the intake valve, C, to the engine cylinder. The ring, H', of said annular vaporizer is provided in its lower portion with a recess, m, which receives the electric appliance or rheostat heretofore described as consisting of a resistance wire or ribbon adapted to be insulated electrically from metallic contact with the body or mass of metal by interposed layers of mica. The resistance wire or ribbon, h², indicated by dotted lines in said Fig. 2, is coiled on a mica core, h⁴, and said core and the resistance are between insulating mica layers, h³, the latter being in contact with the mass of metal formed by the ring or annulus, H', said mica layers, h³, and the core, h⁴, being in the form of rings. The electrical current is supplied to and returned from the resistance, h², by the conductors, j, which lead through the insulating bushing, k. The annulus or ring, H', of said vaporizer is provided, furthermore, with a chamber, n, above the recess, m, and this chamber of the annular vaporizer is in communication with passages, n', which establish communication between the chamber, n, of the vaporizer with the circulating chamber, d', of the cylinder head, whereby the water, or other cooling medium, may be caused to circulate through the vaporizer, H', when the engine is in service.

When the intake valve is opened the mixture of air and liquid combustible flows into the open space of the vaporizer, H', the inclined surface of said valve, C, operating to direct the aforesaid mixture into contact with the inner surface of said annular vaporizer. The vaporizer being heated by an electrical current before the engine is started, the admission of the first charge of explosive mixture of the engine cylinder brings the liquid combustible of such charge into contact with the hot surface of said annular vaporizer, so that the liquid combustible is converted into vapor, the latter being exploded by the operation of the igniter. After the engine shall have been started into operation, the electric current is switched off from the vaporizer,

and the water circulating through the cylinder head, B, is free to flow through the chamber, m, of said vaporizer, thus preventing the latter from becoming unduly heated and obviating deterioration of the metal and the electrical resistance constituting said vaporizer.

In Figs. 3 and 4 of the drawings we have shown another form of electrically heated and water cooled vaporizer, the same being indicated generally by the reference character h². In this form of our invention we employ concentric tubes, o, o', and an interposed electrical resistance or rheostat between said concentric tubes. Preferably the tubes are bent into the annular form shown in Fig. 4, and the inner tube is provided with vertical legs, p, p', said legs being adapted to be extended through the cylinder head, B, whereby one of said legs may be connected with a circulating pipe, P, while the other leg may connect with another circulating pipe (not shown). The pipe, P, is shown as having a controlling valve, p², adapted to be closed for shutting off the circulation of water through the vaporizer when it is to be heated electrically prior to starting the engine. A layer, q', of insulating material, preferably of mica, is wound or wrapped around the inner tube, o', and on this insulating layer is coiled or wrapped an electrical resistance, q, the latter being composed, preferably, of a thin metallic wire or ribbon of the character indicated in Figs. 2 and 5. Around this wire or ribbon forming the resistance is placed another layer, q², of insulating material, preferably of mica, whereby the electrical resistance is inclosed between layers of mica, q', q², the effect of which is to electrically insulate the resistance wire or ribbon from metallic contact with the mass of metal composing the tubes, o, o', of the vaporizer, although the resistance is practically in mechanical contact with said tubes.

In practice we prefer to employ two copper tubes, one of which is smaller in diameter than the other, and while the tubes are in straight condition we apply the insulating layer, q', to the smaller tube, o'. The resistance wire or ribbon is now coiled on said layer and then the other insulating layer is wrapped around the resistance, after which the prepared inner tube, the resistance, and the insulating layers, are incased within the outer tube, o. Finally the assembled parts are bent to the annular or ring like form shown in the drawings, and the ends of the inner tube are then bent upwardly to produce the legs, p, p', thus completing the vaporizer and making it ready for installation into the combustion chamber. Said vaporizer is adapted to be suspended from the cylinder head, B, by hangers, r, or their equivalents, whereby the vaporizer is disposed below the

intake valve, C, so as to be in the path of the inflowing charge of liquid combustible.

It is evident that prior to starting the engine, the electric current is admitted to the resistance, q , for the purpose of heating the tubes, o , o' , so that on the admission of the mixture to the engine cylinder the liquid combustible contained in said mixture will be converted into vapor by contact with the hot surface of the vaporizer, H^2 . After the engine is started, the electrical current is switched from the resistance, q , but to prevent the vaporizer from becoming too highly heated, the valve, p^2 , is opened for the purpose of admitting water or other cooling medium to the inner tube, o' , of the vaporizer, whereby the latter is cooled when the engine is in operation.

Under the generic aspect of our invention, which contemplates the location of a vaporizer within the combustion chamber or piston cylinder of a combustion engine, and means for electrically heating the said vaporizer when starting the engine, we may employ an electrical heater or rheostat in connection with the intake valve employed for admitting a liquid combustible to said cylinder or combustion chamber. Said intake valve is so constructed as to embody a mass of heat absorbing metal containing an inclosed electrical resistance adapted to be supplied with a current of electrical energy, whereby the resistance develops heat adapted to be transmitted to the body or mass of metal formed by said intake valve. The electrical resistance constituting the electrical heater is constructed and arranged for operation in substantially the manner heretofore described.

Having thus fully described the invention, what we claim as new, and desire to secure by Letters Patent is:

1. In a starting vaporizer for internal combustion engines, a combustion chamber, a vaporizing member substantially inclosed within said combustion chamber, electrical means for initially heating said vaporizing member, said vaporizing member being provided with a chamber or passage for the circulation of a cooling medium in contact with the walls thereof, and means whereby a cooling medium may circulate in the chamber or passage of said vaporizing member.

2. In an apparatus of the class described, a chamber, a vaporizer having electric means incased therein for initially heating the same, said vaporizer being positioned within said chamber, and means for securing the circulation of a cooling medium through said vaporizer.

3. In an apparatus of the class described, a chamber, a hollow vaporizer positioned therein, electric means for initially heating

said vaporizer, and means for cooling said vaporizer.

4. In an apparatus of the class described, a combustion chamber, a vaporizer positioned within said chamber and having a substantially annular chamber for the circulation of a cooling medium, and means for electrically heating said vaporizer.

5. In an apparatus of the class described, a combustion chamber, a chambered vaporizer positioned therein, electric means for initially heating said vaporizer, and means for establishing the circulation of a cooling medium in said vaporizer.

6. In an apparatus of the class described, a chamber, a tubular vaporizer positioned therein, said tubular vaporizer forming a chamber for the circulation of a cooling medium therethrough, and electric means for initially heating said vaporizer.

7. In an apparatus of the class described, a vaporizer composed of concentric tubes, means whereby a cooling medium may circulate through one of such tubes, and an electrical resistance inclosed by the tubes and adapted to initially heat the vaporizer.

8. In an apparatus of the class described, a combustion chamber, an intake valve, a chambered vaporizer in said chamber and composed of a mass of heat absorbing metal exposed for contact with a liquid combustible admitted by said valve, means whereby a cooling medium may circulate through the chamber of said vaporizer, and means for electrically heating said vaporizer.

9. In an apparatus of the class described, a vaporizer composed of a mass of heat absorbing metal, an electrically operated heater in said mass of metal, and means whereby a cooling medium is adapted to circulate in contact with said metallic mass.

10. In a starting vaporizer for internal combustion engines, a chamber having an inlet for a liquid combustible, a vaporizing member positioned in said chamber for contact with the liquid combustible, said vaporizing member being composed of a chambered mass of heat-absorbing metal, means for initially heating the vaporizing member, and means for establishing the circulation of a cooling medium in contact with the walls of said vaporizing member.

11. In an apparatus of the class described, a combustion chamber having a fuel inlet, a vaporizer positioned within said chamber and in the path of fuel admitted by said fuel inlet, said vaporizer comprising a chambered mass of heat absorbing metal through which a cooling medium is adapted to circulate, and an electrically operated heater incased by said metallic mass for initially heating the same.

12. In an internal combustion engine, a

combustion chamber, a starting vaporizer positioned within said combustion chamber for contact with a liquid combustible adapted to be supplied to said chamber, said starting vaporizer being composed of concentric tubes, and an electrical resistance incased by one of said tubes, whereby the heat developed by the resistance is absorbed quickly by said tubes.

In testimony whereof we have signed our names to this specification in the presence of two subscribing witnesses.
